UNITED STATES PATENT OFFICE.

MARIUS J. WISBY, OF RACINE, WISCONSIN, ASSIGNOR TO HARTMANN TRUNK COMPANY, OF RACINE, WISCONSIN, A CORPORATION OF WISCONSIN.

GARMENT-RETAINER BAR.

Application filed September 27, 1926. Serial No. 138,040.

This invention relates to improvements in garment retainer bars, particularly adapted for use in suitcases.

Suitcases and trunks of the wardrobe type are provided with a wardrobe section in which the garments are suspended by hangers, and the garments are engaged medially of their length by a retainer for maintaining the garments in place during transportation.

It is one of the objects of the present invention to provide a flexible garment retainer bar for the purpose described.

A further object of the invention is to provide a yielding retainer bar to eliminate injury to the garments.

A further object of the invention is to provide a garment retainer which may be easily adjusted to various positions of use, or removed from the wardrobe section when desired.

A further object of the invention is to provide a retainer bar in which the complementary clasp portions may be stamped from sheet metal.

A further object of the invention is to provide a retainer bar which is of very simple construction, eliminates mechanically operated portions, is inexpensive to manufacture, is strong and durable, and is well adapted for the purpose described.

With the above and other objects in view, the invention consists of the improved garment retainer bar for wardrobe suitcases and the like, and its parts and combinations as set forth in the claims, and all equivalents thereof.

In the accompanying drawing in which the same reference characters indicate the same parts in all of the views:

Fig. 1 is a cross sectional view through the wardrobe section of a trunk or suitcase showing the improved retainer bar;

Fig. 2 is a fragmentary front view of a wardrobe section showing the retainer bar;

Fig. 3 is an enlarged cross sectional view through one side of a wardrobe section and the clasp portions of the retainer bar; and

Fig. 4 is a view taken on line 4—4 of Fig. 3.

Referring now more particularly to the drawings, it will appear that the numeral 6 indicates the wardrobe section of a trunk or suitcase, said wardrobe section having an open front.

Guide members 7 mounted on the inner opposite sides of the wardrobe section are spaced from the walls thereof by the offset end portions 7' and are secured to the walls by rivets or screws 8. A plurality of spaced apart apertures 9 are formed in the guide members 7.

A flexible retainer bar 10 is adapted to extend between the guide members 7 and said retainer bar is formed of an inner core 11 of canvas or other similar stiffening material, covered, except at the end portions, by plush or other suitable soft material, as indicated at 12. Each end portion of the member 10 is looped over and movably embraces the cross bar 13 of a metallic clasp member 14, each clasp member being adapted for adjustable engagement with the guide members 7 to hold the retainer bar in position within the wardrobe section.

The clasp members are V-shaped with a manipulating portion 15 extending outwardly from the engaging portion 16. Each engaging portion 16 of the clasps is provided with a T-shaped slot 17 to receive the guide member 7 there adjacent, and projecting forwardly from the slot is an angular stud or lug portion 18 for selective engagement with any of the apertures 9 of said guide member.

When the retainer bar is attached to the guide members, as shown in the drawing, the lug portions of the clasps will engage corresponding apertures in the guide members to hold the retainer in adjusted position. Any outward pressure exerted by the clothing will tend to prevent disengagement of the clasps from the guides. However, when it is desired to readjust or remove the retainer bar, the clasps are pushed slightly to the dotted line position shown in Fig. 3, wherein the lug portions 18 are disengaged from the apertures 9, and the device may then be moved longitudinally on the guide members.

From the foregoing description, it will be seen that the improved garment retainer bar may be used in either suitcases, trunks, or other wardrobe containers, and is of very simple and novel construction.

What I claim as my invention is:

1. The combination with a wardrobe container, of a garment retainer therefor, comprising a guide member connected to each opposite inner side of the container and having openings, and a retainer bar extend-

ing between the guide members and having at both ends one-piece clasp portions slidably engageable with any portions of the entire lengths of said guide members, said 5 clasp portions having fixed lug portions which enter said openings.

2. The combination with a wardrobe container, of a garment retainer therefor, comprising guide members connected to opposite 10 inner sides of the container, a retainer bar extending between the guide members, and one piece clasp members tiltably and non-rigidly carried by both end portions of said retainer bar and adapted to releasably 15 engage various portions of said guide members without complete detachment from said guide members.

3. The combination with a wardrobe container, of a garment retainer therefor, comprising guide members connected to opposite 20 inner sides of the container and having openings, a retainer bar extending between the guide members, and one-piece clasp members movably carried by the end portions of the 25 retainer bar and slidably engaging said guide

members, each clasp member having a fixed projecting lug adapted to engage any of said guide openings, the lug being engaged upon an outward pressure on the clasp member and released upon an inward pressure thereon.

4. The combination with a wardrobe trunk section, of a garment retainer therefor, comprising guide members connected to opposite inner sides of the trunk section 30 and having openings therein, a flexible retainer bar extending between the guide members, and slotted clasp members movably carried by the end portions of the retainer bar, the guide members being received by the slotted portions of the clasp members to permit sliding movement of the clasps and retainer bar with respect to the guide members, each clasp member having a projecting lug portion for selective engagement with 35 any of the openings of its guide member, the lug being releasable therefrom upon a tilting movement of the clasp member.

In testimony whereof, I affix my signature.

MARIUS J. WISBY.
